CLAIM

The ornamental design for a combined needle disposal container and glove dispenser, as shown and described.

DESCRIPTION

FIG. 1 is a front elevational view of combined needle disposal container and glove dispenser according to my invention;

FIG. 2 is a side elevational view thereof, from the right of FIG. 1;

FIG. 3 is a side elevational view of the opposite side thereof;

FIG. 4 is a top plan view thereof;

FIG. 5 is a bottom plan view thereof; and,

FIG. 6 is a rear elevational view thereof.
